UNITED STATES PATENT OFFICE.

CARL A. PETERSON, OF CHICAGO, ILLINOIS, ASSIGNOR TO AMERICAN BRAKE SHOE & FOUNDRY COMPANY, OF MAHWAH, NEW JERSEY, A CORPORATION OF NEW JERSEY.

APPARATUS FOR CLEANSING CASTINGS.

1,159,707.

Specification of Letters Patent.

Patented Nov. 9, 1915.

Application filed January 2, 1915. Serial No. 52.

To all whom it may concern:

Be it known that I, CARL A. PETERSON, a citizen of the United States, and a resident of Chicago, in the county of Cook and State of Illinois, have made and invented certain new and useful Improvements in Apparatus for Cleansing Castings, of which the following is a specification.

This invention relates to an apparatus or mechanism for the ejection of a casting from its containing flask, and the subsequent cleansing thereof and delivery to a conveyer.

The efficient removal of hot castings from their flasks and cleansing of sand has always been a serious problem in foundries, and more especially in those wherein a large number of relatively small castings are produced. The elimination of the greater part of the manual labor ordinarily expended in the breaking up of the molds and cleansing of the castings, will therefore materially decrease the cost of castings.

One of the prime objects of the present invention is the provision of mechanical means whereby the contents of a mold or flask may be forcibly ejected and deposited upon a rotating grate for the separation of the sand and castings, and cleansing of the latter, as well as, its subsequent delivery to a conveyer.

A further object is to provide a mechanism adapted to engage the outstanding lugs of the drag of a mold and by the application of a suitable force, such as compressed air, elevate the mold, and in so doing, swing the same above the open extremity of a rotating grate. The casting is then forcibly ejected from the mold, and delivered upon the grate for its cleansing and subsequent discharge to a suitable conveyer.

A further object is to provide a conical grate for the reception and cleansing of the contents of molds and to so mount the grate, that castings may be dropped directly there-in and will gradually work their way toward the lower and open extremity of the grate, for their discharge upon a suitable conveyer.

Further objects and advantages will appear as the description proceeds, wherein it is understood that changes in the precise embodiment of the invention can be made within the scope of what is claimed, with-

out departing from the spirit of the invention. 55

The preferred embodiment of my invention is illustrated in the drawings, in which:—

Figure 1 is a view in top plan of the apparatus embodying my invention. Fig. 2 60 is a view of the foregoing, partially in side elevation, and partially in section, and illustrating by full and dotted lines the several positions of the flask engaging and casting ejecting member. Fig. 3 is a view in longitudinal section of the casting ejecting member, illustrating the same supporting a mold and with the various parts in position prior to the ejection of the mold contents. Fig. 4 65 is a view in top plan of the casting ejector. 70

Referring more particularly to the several views, wherein similar reference numerals designate corresponding parts throughout, a delivery conveyer 6 is adapted to conduct the hot molds 7 to a point directly in front 75 of a rotating grate 8. The grate is substantially frusto-conical in configuration and includes the end rings 9 and 10, between, and to which, the grate bars 11 are secured. Suitable rollers 12 are mounted upon the inclined shafts 13, and rotatably support the frusto-conical grate in an inclined position, the grate sloping downward toward its smaller open extremity. A chain 14, or 80 analogous power transmitting means, is connected to one of the shafts 13, providing for the mechanical actuation of the grate. 85

A swinging boom 15 projects outwardly from a wall or support 16 and constitutes an overhead track upon which a carriage 17, 90 including a wheel 18, is movably mounted. An ejector and flask engaging member 19 is rigidly secured to and depends from the carriage 17, and is of the pneumatic type, including the cylinder 20, and piston 21. A 95 piston rod 22 is rigidly secured to the piston 21, projects through the upper end 23 of the cylinder and is rigidly secured at its upper extremity to, or formed as a part of, the carriage 17. The remote extremity of the 100 piston rod projects through the lower cylinder end 24, and carries the head or block 25. Thus, as air or steam under pressure is admitted to the cylinder above the piston 21, from the supply pipe 26, the cylinder will 105 be forcibly raised and maintained in an

elevated position until such time as the three-way controlling valve 27 is moved into a position in which the pressure supply is closed, and the cylinder brought into communication with the exhaust pipe 28.

Pivots secured to the lower end 24 of the ejector cylinder are the grappling arms 29, bent intermediate their ends, and provided at their lower extremities with the fingers 30, so designed and arranged as to engage the outstanding lugs 31, with which the flasks are ordinarily provided. The grappling arms extend to both sides of their pivotal mountings, and are provided with the links 32, connecting their free ends. A handle 33 projects from one of the grappling arms and provides for their convenient manipulation, allowing the gripping fingers to be readily brought into engagement with the flask lugs.

The overhead track or boom 15 is so situated that it may swing directly above the rotating frusto-conical grate, as illustrated in Fig. 1, allowing portions of the ejector to swing within the upper and open extremity of the grate, to thus insure that the casting, discharged from the flask, will enter the grate and be separated from the other mold constituents. The rotating of the grate results in the tumbling and cleansing of the casting, its separation from the sand, and its discharge from the lower and open extremity of the grate upon a conveyer 34, located therebelow.

As the delivery conveyer brings a hot mold in front of the rotating grate, the operator, by a suitable manipulation of the handle 33 and controlling valve 27, swings the ejector into position. The three-way valve 27 is then opened, resulting in the admission of pressure within the cylinder and the forced raising thereof, and in so doing, the ejector is allowed to swing into the position illustrated in full lines in Fig. 2.

As the ejector cylinder rises, the mold is brought into forcible contact with the head 25, and a further elevation thereof causes the mold to move above the said head 25, resulting in the forced ejection of the constituents thereof; the casting and sand dropping into the open extremity of the frusto-conical grate above which the ejector has previously swung. The obliquity of the grate axis results in the inclination of the plane of the upper open extremity of the grate, which allows the casting to drop directly therein. The obliquity of the axis is relatively greater than that of the side walls of the grate, so that a downward slant will also be

present in the lower side walls of the grate, whereby the castings will gradually work their way toward the lower discharge extremity of the grate, as they are tumbled about therein. From the foregoing, it will

be apparent that hot molds may be successfully handled, and their contents conveniently and quickly discharged, the castings although still in a heated condition being delivered or discharged directly into a suitable mechanism, wherein they are cleansed of the mold sand; the action being almost entirely automatic and allowing a large number of molds to be treated in a relatively short time and with the expenditure of little manual labor.

What I claim is:—

1. An apparatus of the class described comprising a member adapted to engage and raise a mold, means carried by said member adapted to eject the contents therefrom, and an inclined rotatable grate with open extremities adapted to receive said mold therein for the direct discharge of the contents of said mold into said grate.

2. An apparatus of the class described comprising a flask engaging member, means carried by said member adapted to raise said flask and eject the contents thereof, and a rotatably mounted frusto-conical grate with open extremities, the axis of said grate disposed at an angle to the horizontal providing for the vertical discharge of the flask contents into said grate, the upper open extremity of said grate adapted to receive said flask therein.

3. An apparatus of the class described comprising a delivery conveyer, an ejector mounted thereabove and including means for engaging a mold and adapted to elevate the same, means carried by said ejector adapted to discharge the contents of said mold during the elevation thereof, and an open-ended rotatably mounted grate with the axis thereof inclined at an angle to the horizontal adapted to receive the contents of the mold therein as the ejector swings thereabove.

4. An apparatus of the class described comprising a delivery conveyer, an ejector mounted thereabove and including means for engaging a mold and adapted to elevate the same, means carried by said ejector adapted to discharge the contents of said mold during and by virtue of the elevation thereof, and an open-ended rotatably mounted grate with the axis thereof inclined at an angle to the horizontal adapted to receive the contents of the mold therein as the ejector swings thereabove, and a conveyer located beneath the lower discharge extremity of said grate adapted to receive the castings as they are discharged from said grate.

5. An apparatus of the class described comprising a substantially frusto-conical grate including end rings; spaced bars extending therebetween; means engaging these rings rotatably supporting the same and

mounting said grate in an inclined position,
the obliquity of the axis being greater than
the obliquity of the sides, and means for
delivering castings to the open upper ex-
5 tremity of said grate.

Signed at Chicago in the county of Cook

and State of Illinois this eighteenth day of
December A. D. 1914.
